CLAIM

The ornamental design for a battery module as shown and described.

DESCRIPTION

1.1 is a perspective view of a battery module showing our new design;

1.2 is another perspective view thereof;

1.3 is a right side view thereof;

1.4 is an enlarged view thereof;

1.5 is a front view thereof;

1.6 is an enlarged view thereof;

1.7 is a top view thereof;

1.8 is an enlarged view thereof;

1.9 is a back side view thereof; and

1.10 is an exploded view thereof.

1.1: the depiction shows a battery module with a handle mounted; **1.2**: the depiction shows a partial view of the battery module without the handle; **1.3**: the depiction shows a battery module with a handle mounted; **1.4**: the depiction shows a partial view of the battery module without the handle; **1.5**: the depiction shows a battery module with a handle mounted; **1.6**: the depiction shows a partial view of the battery module without the handle; **1.7**: the depiction shows a battery module with a handle mounted; **1.8**: the depiction shows a partial view of the battery module without the handle; and **1.10** is an enlargement of **1.2** with portions exploded to show more detail.

The broken lines shown in the drawings depict portions of the article which form no part of the claimed design.

1 Claim, 10 Drawing Sheets
